APPARATUS FOR HANDLING FLAT MATERIAL

Lee Sekulski, Ellwood City, Pa., assignor to
Mathews Conveyer Company, Ellwood City,
Pa., a corporation of Pennsylvania

Application September 24, 1931, Serial No. 564,830
Renewed July 26, 1935

23 Claims. (Cl. 214—1)

This invention relates to an improved apparatus for handling flat material such, for example, as wall and building boards, and various other sheet like articles.

5 In manufacturing plants where it is desired to increase the production of their products by adding new manufacturing units, it frequently happens that the building accommodations will not permit the setting of the machinery for straight 10 line production. In some cases ground space is not available to enlarge or lengthen the building. In other cases there would be no economy in enlarging the building for the purpose of installing new units, if a means could be provided for 15 transferring the product from one line to another production line disposed at right angles or 90° from the first. With this in mind, the present transfer unit was designed. It is particularly 20 adapted for handling flat material such, for example, as wall and building boards, and other sheet-like articles. An advantage of this novel transfer unit is that it can be used for the dual purpose of selectively transferring articles from a main line conveyer onto a production line situated adjacent to one side of the transfer unit, or 25 the articles may be transferred onto a production line situated in line with the main line conveyer for continuing production in a straight line. This will be more clearly defined in the following 30 specification.

An object of the invention is to provide an apparatus for handling flat articles comprising means for selectively transferring the articles from one elevation to another.

35 A further object is to provide an apparatus which may be termed a transfer unit, adapted to receive sheet like articles or material from a suitable feeding means and transferring them to a selected elevation, said unit comprising means whereby the articles may be diverted from their normal line of travel onto a suitable receiving means positioned adjacent to one side therefor, if desired, they may be directed into a receiving 40 means situated substantially in the line of travel of the articles when fed into the unit.

45 A further object is to provide a transfer unit particularly applicable for use in the handling of wet composition boards such as are used in the building trade, said unit being adapted to receive the wet boards directly from the usual press through which the boards pass from the forming machine, and transferring them onto the usual superposed tiers or racks of an ordinary drying oven, said unit comprising means whereby it 50 may be operated to deliver the boards into selected tiers or racks of drying ovens stationed at different locations with respect thereto.

55 A further object is to provide a transfer unit comprising means for feeding the articles lengthwise thereof for delivery into a suitable receiving

means situated at one end thereof, and also having means whereby the articles may be moved laterally therefrom onto a receiving means positioned to one side of the line of travel of the articles when received on said unit.

5 A further object is to provide such an apparatus including a vertically movable platform or elevator comprising a plurality of belts adapted to receive the boards or articles from a suitable feeding means, and a plurality of conveyer rollers disposed substantially parallel to the line of travel of the articles as they are delivered onto said belts, and means being provided whereby said conveyer belts may be rendered inoperative for feeding articles, and whereby said conveyer rollers 10 will be made operative to laterally feed the articles from the elevator.

15 A further object is to provide a transfer unit comprising a main supporting frame having an elevator mounted therein and provided with an independent operating motor, and a control mechanism being provided for said motor comprising a suitable selector switch situated at an operator's station and comprising a plurality of 20 switch buttons, one for each elevation adapted to receive articles from the elevator, whereby when an article is delivered onto the elevator, the operator may manipulate the switch button of a selected station whereby the motor will operate 25 to move the elevator to said selected elevation at which station it will automatically come to rest, said unit also comprising a plurality of other control buttons for controlling the operation of other motors operating to feed articles onto the elevator, and to actuate the belts and conveyer 30 rollers of the elevator.

35 Other objects of the invention reside in the construction of the elevator of the transfer unit whereby articles received thereon may be discharged therefrom in a direction either lengthwise of the conveyer belts of the elevator or in a direction transversely with respect to said belts; in the means provided for automatically interrupting the travel of articles delivered onto the elevator; in the electrical control mechanism for controlling the operation of the transfer unit; in the means provided for moving the conveyer belts of the elevator into and out of operative 40 positions; in the means provided for automatically limiting the vertical travel of the elevator; and in the general construction of the apparatus, as a whole, and in the organization of the various mechanisms whereby the operation of the entire apparatus may be conveniently controlled from 45 an operator's station.

50 Other objects of the invention will appear from the following description and accompanying drawings and will be pointed out in the annexed claims.

55 In the accompanying drawings, there has been 60

disclosed a structure designed to carry out the various objects of the invention, but it is to be understood that the invention is not confined to the exact features shown as various changes may 5 be made within the scope of the claims which follow.

In the drawings:

Figure 1 is a side elevation partially in section showing the elevator in its normal load receiving 10 position, and also showing the power-operated feeding conveyer for delivering articles to the transfer unit;

Figure 2 is a plan view of Figure 1 with some 15 of the parts omitted;

15 Figure 3 is an enlarged sectional plan view on the line 3—3 of Figure 1, partially broken away to more clearly show the construction of the operating mechanism;

20 Figure 4 is a longitudinal sectional view on the line 4—4 of Figure 3, showing the conveyer belts of the elevator in operative position;

25 Figure 5 is a sectional view on the line 5—5 of Figure 3, showing the conveyer belts of the elevator in inoperative position;

25 Figure 6 is a sectional view on the line 6—6 of Figure 4, showing the means for supporting the elevator;

30 Figure 7 is a detail sectional view on the line 7—7 of Figure 4, showing the conveyer belts of the elevator in operative positions;

Figure 8 is an enlarged detail view showing the control panels of the apparatus;

35 Figure 9 is a diagrammatic view illustrating the connections between the control valve and the cylinders which control the operation of the conveyer belts of the elevator;

40 Figure 10 is a diagrammatic view illustrating the transfer unit situated so as to be capable of delivering articles into two different receiving means or drying units;

Figure 11 is a wiring diagram diagrammatically illustrating the electrical connections between the various control instruments;

45 Figure 12 is an enlarged detail view diagrammatically illustrating one of the sets of contacts employed in the selector switch used for controlling the operation of the elevator; and

50 Figure 13 is a wiring diagram illustrating the electrical connections of the motor which operates the conveyer belts of the elevator and other electrical instruments associated therewith.

To afford a clear explanation of the invention herein disclosed, the transfer unit is shown used in connection with a press, such as is commonly 55 used in the manufacture of composition boards, and through which the wet boards are passed for the purpose of removing the surplus water or liquid therefrom. From the press, the wet boards are usually delivered to a drying oven comprising 60 a plurality of superposed conveyers or tiers, and the transfer unit herein disclosed readily lends itself for use to selectively transfer the wet boards from the press onto the various tiers in the drier. As the press and drier form no part of the present 65 invention, they are only diagrammatically illustrated in the drawings.

In Figure 1, 2 represents the discharge end of a suitable press, and 3 and 4 driers arranged adjacent to the transfer unit, the latter being generally indicated by the numeral 5, in Figure 10.

The transfer unit is shown comprising a structural frame having uprights 6 and 7 at the receiving end thereof and similar uprights 8 and 9 at the opposite end thereof. These uprights are 75 preferably of angle iron cross section and are se-

cured together at the receiving end of the unit by suitable cross members 11, 12, and 13, and at the opposite end of the structure by similar cross members 14 and 15. The upper ends of the uprights 6, 7, and 8, 9, are shown secured together 5 lengthwise of the structure by suitable channels 15—15, having cross members 16 interposed therebetween, as shown in Figure 2. Suitable diagonal braces 17 are provided at the corners of the structure, as shown. The lower portions of the uprights 6, 7, and 8, 9, are secured together lengthwise of the structure by suitable frame members 18 and 19, as shown in Figures 1, 6, and 8.

A vertically movable platform, hereinafter referred to as the elevator, is mounted in the structural frame above described, and comprises side rails 21 and 22 secured together at their ends by suitable cross members 23, and at their intermediate portions by a cross member 24. The side rails 21, 22, and cross members 23—23 and 24 20 cooperate to provide a rectangularly shaped frame, as best shown in Figure 3.

The elevator frame is movably supported by suitable chains 25 mounted upon sprockets 26 and 27 provided at each end of the supporting frame, as best shown in Figures 1, 4, and 6. The sprockets 26 are supported upon suitable cross shafts 28 mounted in suitable bearings provided at the upper portion of the supporting frame, and the lower sprockets 27 are similarly mounted upon 30 cross shafts 29 suitably mounted in the lower portion of the main supporting frame. The elevator frame is provided at its corners with angle brackets 30 which are secured to links of the chains 25, as best shown in Figures 3 and 6. Thus, when the chains are operated by rotation of the sprockets 26 and 27, the elevator frame will be correspondingly operated.

The means for operating the elevator chains 25 is best shown in Figures 1 and 2, and comprises a motor 31 mounted upon a platform 32 supported between the intermediate cross members 16 at the upper portion of the main supporting frame. A suitable speed reducer 33, of ordinary construction, is operatively connected with the 45 motor through a flexible coupling 34. The shaft 35 of the speed reducer is connected at its opposite ends with drive shafts 36—36 by suitable flexible couplings 37—37. The drive shafts 36 are geared to the upper cross shafts 28 by suitable bevel gears 38 and 39. The motor 31 is of the reversible type so that when operated in one direction, the elevator will ascend, and when operated in the opposite direction, it will descend. Suitable counter-weights 41 are secured to cross 50 beams 42 secured to the chains 25. These counter-weights are arranged to travel between the uprights 6 and 7 at one end of the main frame and between the uprights 8 and 9 at the opposite end of the frame, and function to substantially 55 counterbalance the weight of the elevator.

An important feature of the invention resides in the novel construction of the elevator whereby articles or boards delivered thereto may be laterally discharged therefrom at a selected elevation or drier tier. Secured to the upper portions of the cross rails 23—23 and 24 of the elevator frame, are a plurality of longitudinally extending rails 43, 44, 45, and 46, upon which are secured cross members 47 and 48. Cross shafts 49 and 51 are mounted in suitable bearings 52—52 and 53—53, respectively, secured to the longitudinally extending rails 43, 44, 45, and 46, as best shown in Figures 3 and 6. A plurality of pulleys 54 are secured to the cross shafts 49 and 51 and are 75

spaced equidistant apart thereon, as best shown in Figure 3. Suitable conveyer belts 55 are mounted upon the pulleys 54 and are disposed lengthwise of the elevator in spaced parallel relation. Onto these belts, the boards are delivered from a suitable live roller feeding conveyer, indicated generally by the numeral 56 in Figure 1. This feeding conveyer is here shown interposed between the press 2 and the transfer unit, and 10 provides means for feeding the boards from the press onto the elevator.

The feeding conveyer 56 comprises a plurality of conveyer rollers 57 mounted in suitable frame members 58 and adapted to be driven by a belt 59, the upper run of which is held in frictional contact with the lower portions of the conveyer rollers 57 by means of suitable rollers 61. The belt 59 is driven by a motor 62 operatively connected therewith by a suitable speed reducer 63 and chain drive 64. One end of the feeding conveyer 56 may be supported upon the uprights 6-6 of the main supporting frame of the transfer unit, and the opposite end thereof directly upon the frame of the press, as illustrated in 25 Figure 1.

In order to laterally discharge the boards or articles from the elevator into a tier of the drier 3, a plurality of longitudinally extending rollers 65 are mounted upon the cross rails 47 and 48 secured to the longitudinally extending rails 43, 44, 45, and 46. These rollers are arranged between the conveyer belts 55, as shown in Figures 3 and 7, and are all operatively connected together for rotation in one direction by means of a suitable chain 66 engaging a sprocket 67 provided at one end of each roller. Suitable idler sprockets 68 hold the upper section of the chain in engagement with the teeth of the sprockets 67. Other idler sprockets 69 guide the lower run of the chain over the rails 44, 45, and 46, and also prevent the lower run of the chain from engaging the teeth of the sprockets 68.

The drive chain 66 of the rollers 65 is driven by a sprocket 71 secured to a short shaft 72 mounted in suitable bearings 73 and 74, and having a beveled gear drive 75 connecting it with a speed reducer 76 of ordinary construction. The speed reducer 76 is connected by a flexible coupling 77 to a motor 78 which preferably is adapted for continuous operation so that the rollers 65 will rotate continually.

The conveyer belts 55 are driven by a motor 79 similar to the motor 78 and have a flexible coupling 81 connecting it with a speed reducer 82 connected by a flexible coupling 83 to one end of the shaft 51 upon which the pulleys 54 at one end of the elevator are secured. The motors 78 and 79 are mounted upon suitable plates or platforms 84 and 85 secured to the rectangular frame 60 of the elevator.

To render the conveyer rollers 65 of the elevator operable to laterally discharge a board from the elevator, means are provided for lowering the upper runs of the conveyer belts 55 beneath the upper portions of the peripheries of the rollers 65 so that the weight of the board will be transferred from the belts 55 directly onto the peripheries of the rollers 65, whereby the board will be discharged laterally from the elevator.

The means provided for thus actuating the conveyer belts 55 is best shown in Figures 4, 5, and 7, and comprises a plate 86 mounted for relative vertical movement upon the elevator in suitable guides 87 secured to the longitudinally 75 extending rails 43 and 46. Depending studs 88

are secured to the plate 86 at the corners thereof and are slidably supported in the guides 87. (See Figures 4 and 5.) Supported upon the plate 86, directly beneath the upper run of each belt 55, are a plurality of snub rollers 89 supported by suitable channels 91 secured to the plate 86. When the plate is in the position shown in Figure 4, the snub rollers 89 will be in engagement with the upper runs of the belts 55 and will support them in the elevated positions shown in Figures 4 and 7, wherein it will be noted that a board supported thereon will be out of engagement with the peripheries of the rollers 65, as indicated by the dotted lines in Figure 7. Conversely, when the snub rollers 89 are lowered to the position shown in Figure 5, they will disengage the upper runs of the belts 55 wherein they will move to the position shown in Figure 5 substantially beneath the upper portions of the peripheries of the rollers 65. When the belts are thus positioned, the board will be supported directly upon the rollers 65, as indicated by the dotted lines in Figure 5, whereby it will be laterally discharged from the elevator.

The means for actuating the plate 86 is shown comprising a pair of rock shafts 92, mounted in suitable bearings 90 secured to the rails 43, 44, 45, and 46, as shown in Figure 7. Crank arms 93 are secured to the shafts 92 and are connected by links 94 to angle brackets 95, secured to the bottom of the plate 86. Depending arms 96 are also secured to the rock shaft 92 and have their lower ends pivotally connected together by a suitable connection 97, whereby the arms 96 are disposed in substantially parallel relation. The connection 97 is preferably forked at one end, as shown at 98 in Figure 3, whereby the arms 96 secured to the rock shaft 92 adjacent to the receiving end of the elevator, will be spaced apart as shown in Figures 3 and 7. Connecting links 99 connect the forked end of the connection 97 with a cross head 101 mounted for reciprocal movement between guides 102 interposed between two cylinders 103 and 104, secured to a pair of channels 105 which, in turn, are secured at one end to a member 106, and at their opposite ends to the cross member 23 at the receiving end of the elevator frame. Pistons 107 and 108 are mounted in the cylinders 103 and 104, respectively, and are operatively connected with the cross head 101 by suitable piston rods 109.

The pistons 107 and 108 may be operated from a suitable pressure fluid such as compressed air. A pipe 111 connects the head of the cylinder 103 with an outlet 112 of a suitable control valve 113, best shown in Figures 8 and 9. The cylinder 104 has a pipe 114 connecting it with an outlet 115 of the valve 113. A pipe 116 leads from the valve 113 to a suitable source of fluid pressure, not shown. In Figure 9, the valve 113 is diagrammatically illustrated as having at its upper portion an exhaust port 117. The valve is shown having a rotor 118 provided with suitable ducts 119 and 121 capable of establishing communication between the pipes 111, 114, and 116 connected with the valve casing 120. The valve 113 has a suitable operating lever 122 whereby its rotor 118 may be conveniently rotated, and the valve situated convenient to the operator's control station, generally indicated by the numeral 123 in Figures 2 and 10. The valve is mounted upon a suitable fixed support, not shown in the drawings. Because of the cylinders 103 and 104 being mounted upon the frame of the elevator so as to move therewith, the pipes connecting the

cylinders with the valve are provided with suitable flexible connections, or swivel joints, which may be of any suitable construction, and it is therefore thought unnecessary to show the same in the drawings.

By manipulation of the control lever 122 of the valve 113, the pistons 107 and 108 will be caused to reciprocate in their respective cylinders with the result that the rock shafts 92 will be operated, whereby the crank arms 93 will, because of their connections with the plate 86, supporting the snub rollers 89, raise or lower the upper runs of the conveyer belts 55, depending upon the direction of movement of the pistons 107 and 108. When the pistons are in the positions shown in Figures 4 and 9, the upper runs of the conveyer belts 55 will be elevated so as to cause articles delivered onto the elevator to be supported directly upon the belts 55. When the elevator reaches the selected elevation, it will automatically come to rest, as will subsequently be described, and the operator then manipulates the valve 113 so as to cause the air in the cylinder 103 to be expelled therefrom through the exhaust 117 of the valve, while, at the same time, fluid pressure is admitted into the cylinder 104 against the piston 108, thereby causing the cross head to move in a direction towards the left, when viewed as shown in Figures 4 and 9, resulting in the lowering of the belts 55 to the positions shown in Figure 5. Such movement of the cross head will actuate the rock shafts 92 to the positions shown in Figure 5, wherein it will be noted that the article or board will be supported directly upon the conveyer rollers 65, because of the upper runs of the belts 55 being positioned beneath the upper portions of the peripheries of said rollers.

The lower run of each conveyer belt 55 is guidingly supported upon suitable idlers 124 secured to the bottom of the plate 86, and each belt is provided with a suitable counter-weight 125, each having a sheave 126 received in a depending loop 127 of its respective belt, as best shown in Figures 4 and 5. These counter-weights retain the conveyer belts 55 at a uniform tension, regardless of whether they are in a raised or lower position. If necessary, suitable means, not shown, may be provided for guiding the weights 125 and sheaves 126 in their up-and-down movements.

Another feature of this invention resides in the novel control means provided for controlling the operation of the elevator, whereby articles delivered thereto may be raised or lowered to a selected elevation and discharged from the elevator either in a lengthwise direction therefrom or laterally therefrom, as may be desired. As hereinbefore stated, the transfer unit is particularly applicable for use in connection with a board press and one or more driers, which driers are usually provided with a plurality of superposed tiers or conveyers so that articles or boards delivered onto said tiers will be carried slowly through the drier. These driers are of ordinary and well-known construction and it is therefore thought unnecessary to show the same in detail. Portions of the driers are diagrammatically indicated in Figures 1 and 10, and each is shown as comprising eight tiers.

The novel control mechanism employed in connection with the transfer unit comprises a plurality of electrical instruments and mechanisms of well-known construction, so organized and interconnected with the operating mechanism of the transfer unit as to provide a very simple and practical control mechanism which may be con-

veniently operated by an attendant stationed at the control station 123.

As hereinbefore stated, the conveyer rollers 65 of the elevator are operated by the motor 78, which, when the transfer unit is in operation, 5 operates continually. The conveyer belts 55 operate intermittently, and are driven by the motor 79 shown at the lower right hand corner of Figure 3. Means are provided for automatically stopping the motor 79 when a board has been delivered onto the elevator from the feeding conveyer 56, and is here shown as consisting of a stop switch 128 supported upon an overhanging bracket 129 secured to the rail 46 of the elevator frame, as best shown in Figure 7. The 15 switch 128 has a swingable arm 131 provided with a roller 132 adapted to be engaged by a board being conveyed onto the belts 55, as will be clearly understood by reference to Figure 1. The arm 131 carries a movable contact 133 normally engaged with a fixed contact 134 having a wire 135 connecting it with one side of a manually operable stop switch 136, which may be of the push button type and is normally closed, as shown in Figure 13. A wire 137 connects the 25 opposite side of the stop switch 136 with one side of a starter switch 138, also of the push button type, and which normally is in open position, as shown. A wire 139 leads from the wire 131 to a movable contact 141 adapted to 30 engage a fixed contact 142 having a wire 143 connecting it with the opposite side of the starter switch 138. A wire 144 connects the starter switch 138 with one side of a solenoid coil 145, having a wire 146 connecting the opposite end 35 thereof with the conductor 149 of a main line circuit as shown in Figure 13. A wire 151 connects the conductor 148 of the main line circuit with the movable contact 133 of the stop switch 128. 40

The motor 79 has a wire 152 connecting it with a movable contact 153 of the control switch 154, which switch has a second movable contact 155 connected with the motor by a wire 156. The contacts 153 and 155 of the motor switch 154 45 are adapted to be moved into electrical connection with a pair of fixed contacts 157 and 158, respectively, by means of an actuator 159 connected with the movable contacts 141 and 153 and 155, and adapted to be actuated by the solenoid coil 145 when the latter is energized. The actuator is normally retained in the switch opening position shown in Figure 13 by suitable means such as a spring or by gravity.

The fixed contact 157 of the motor switch 154 55 is connected to the main line conductor 149 by a wire 161, and the fixed contact 158 of the switch has a wire 162 connecting it with one end of a brake coil 163, the opposite end of which is connected by a wire 164 to the main line conductor 148. A gap 165 is provided in the wire 162 adapted to be bridged by a member 166 operable by means of a relay coil 167. One end of the coil 167 is connected by a wire 168 to the wire 146 leading from the solenoid 145 to the 60 main line conductor 149. The opposite end of the coil 167 has a wire 169 connecting it with the end of the solenoid 145 to which the wire 144 is connected.

The brake coil 163 is adapted to actuate a 70 magnetic brake which comprises a drum 171 secured to a shaft extension 172 of the speed reducer 82, as indicated in Figure 3. This magnetic brake is of ordinary well-known construction, and comprises oppositely disposed brake 75

shoes 173 adapted to be actuated by a toggle mechanism 174, having an arm 175 provided with an armature 176 positioned within the coil 163. When the coil 163 is energized, the arm 175 will be pulled downwardly, when viewed as shown in Figure 13, whereupon the brake shoes 173 will disengage the drum 171. When the circuit to the coil 163 is open, the brake shoes 173 will automatically be set by the action of a spring 10 177, shown in Figure 13.

The control circuit for the motor 79 operates as follows: When the elevator is in load-receiving position, which, in the present instance, is at elevation No. 3, the board will be fed onto 15 the conveyer belts 55 of the elevator by the feeding conveyer 56. Before the board is delivered onto the elevator, however, the operator will push the starter button 138, whereupon the solenoid coil 145 is energized, thereby causing 20 the movable switch contacts 141, 153, and 155 to move into electrical connection with their respective fixed contacts, resulting in the motor starting. As soon as the contact 141 engages the 25 contact 142, a holding circuit for the actuator 159 is established through the contacts 141 and 142, wires 143 and 144, solenoid coil 145, and wire 146 connected with the main line conductor 149, thence from the conductor 148, through the wire 151, contacts 133 and 134, wire 135, 30 stop switch 136, wire 139, and back to the movable contact 141. At the same time, current flow is established through the coil 167, by reason of one end thereof being connected with the wire 146 by the wire 168, and the opposite end thereof being connected by the wire 169 to the wire 144.

Energization of coil 167 will actuate the member 166 to close the gap in the wire 162, whereupon the magnetic brake coil 163 will be connected in series with the motor and will operate to release the magnetic brake simultaneously as the motor is started. The motor will continue to function until the leading end of the board engages the stop switch 128 and thereby 45 breaks the circuit to the solenoid 145, causing the motor switch 154 to open. At the same instant, the supply of current to the relay coil 167 and brake coil 163 is cut off. It will thus be seen that the stop switch 128 may be actuated by each 50 board delivered onto the elevator, whereby the conveyer belts 55 are automatically interrupted. Operation of the conveyer belts 55 may also be interrupted by manipulation of the manually operable stop switch 136. Under normal operating 55 conditions, and particularly when handling composition boards or other sheet material, the operator need not manipulate the stop switch 136, the motor circuit being automatically opened by the boards engaging and actuating the stop switch 128.

In Figure 10, the transfer unit is shown interposed between the board press 2 and the driers 3 and 4. When thus used, means are provided for rendering the stop switch 128 inoperative, so that 60 when the operator desires to discharge a board from the elevator into one of the tiers of drier 4, situated at the end of the transfer unit, the conveyer belts 55 may continue to function. To thus render the stop switch 128 inoperative, a 65 suitable switch 178, which may be of the push button type, is connected across the contacts of the stop switch 128 so that when a board is to be discharged into one of the tiers of the drier 4, the operator will manipulate the switch 178 and 70 close it, whereupon current flow to the solenoid 75

145 will not be interrupted when the board actuates the switch 128. The operation of the conveyer belts 55 may be interrupted at any time by depression of the stop switch 136. For convenience, the switches 136, 138, and 178 are mounted 5 in a suitable block 179 secured to a control panel 181, mounted on the main supporting frame of the structure adjacent to the operator's station 123.

The motor 78 which operates the conveyer 10 rollers 65 of the elevator is provided with starting and stopping switches 182 and 183, respectively, mounted upon a block 184 similarly secured to the control panel 181. The motor 78 may be operated continuously during operation of the 15 transfer unit, and it is therefore thought unnecessary to show the circuit to this motor in detail, it being an ordinary well-known circuit. In like manner, the circuit to the motor 62 is of well-known construction and is provided with starting 20 and stopping switches 185 and 186, respectively, mounted in a block 187 secured to the control panel 181, as shown in Figures 2 and 8.

The means for controlling the vertical travel of the conveyer is diagrammatically illustrated 25 in Figures 8, 11, and 12, and comprises an ordinary well-known selector switch 188 of the rotary type, diagrammatically illustrated in Figure 8, and shown comprising a shaft 189 having a suitable pulley or wheel 191 mounted thereon. The selector switch may be supported upon a suitable supporting frame 190, as shown. A flexible element 192 such, for example, as a steel band or cable is coiled about the pulley 191 and has one end passing downwardly beneath an idler pulley 193 secured to the lower portion of the main supporting frame of the transfer unit and having its end portion connected with the frame of the elevator for movement therewith. A suitable tension spring 194 may be interposed between the end 40 portion 195 of the flexible element 192 and the elevator frame to allow for variations, and whereby the element will be kept taut. The opposite end portion 196 of the flexible element passes around 45 a guide sheave 197 secured to the main frame of the structure and may be secured to one of the counter-weights 41 by means of a suitable spring 198. By thus connecting the ends of the flexible element to the elevator frame and counter-weights, rotary motion will be imparted to the 50 shaft 189 of the selector switch 188, when the elevator is operated, as will readily be understood by reference to Figure 8. The element or belt 192 is engaged with the pulley 191 in such a manner 55 as to prevent slippage.

In Figure 12, there is diagrammatically illustrated a portion of the mechanism of the selector switch 188, showing the contacts of one elevation. In the present instance, these contacts represent those of elevation No. 3 which, as shown in Figures 1 and 8, is the normal loading station of the elevator. When the elevator is in its normal load receiving position, the mechanism of the selector switch pertaining to that particular station will be positioned substantially as shown 60 in Figure 12. This mechanism comprises an arm 199 secured to the shaft 189 of the selector switch 188 and having a forked end adapted to engage suitable rollers 201 provided upon a contact lever 202 pivoted at 203 and carrying a movable contact 204, adapted to be moved into and out of electrical engagement with fixed contacts 205 and 206, as will be understood by reference to Figure 65 12. The above described switch mechanism is so connected with the elevator that as soon as the 70 75

latter leaves elevation No. 3, either in an upward or a downward direction, the movable contact 204 will electrically engage with one of the two contacts 205 and 206, depending upon the direction of movement of the elevator. As hereinbefore stated, the selector switch 188 is of well-known construction, and it is therefore believed unnecessary to further describe the construction thereof, it being understood that the selector switch comprises a similar set of contacts for each elevation. These are diagrammatically illustrated in Figure 11.

As the electrical connections between the switch contact lever 202 and the parts associated therewith are of similar construction at each elevation, it will be necessary to describe but one such set of connections, the like parts of each of the eight elevations here shown being referred to by like numerals.

20 A wire 207 connects contact 204 with one end of a relay coil 208, the opposite end of which is connected to a terminal 209 of a movable contact 211. The contact 211 is normally in open position and is adapted to engage a fixed contact 212 when the relay 208 is energized. A wire 213 connects the fixed contact 212 with a wire 214, one end of which is connected to a fixed contact 215 of a down limit switch 216 having a movable contact 217 normally engaged with the fixed contact 215. The down limit switch 216 has an arm 218 provided with a roller 219 positioned in the path of the frame of the elevators so that, in the event that the elevator in its downward movement, accidentally passes beyond station No. 35 1, the switch 216 will be opened, resulting in the current supply to the motor 31 being cut off, as will subsequently be described. A wire 221 connects the movable contact 217 of the down limit switch 216 to the main line conductor 148. A 40 wire 226 connects the movable contact 211 of the relay 208 with a terminal 227 of a starter switch 228, comprising four terminals 227, 229, 231 and 232. The terminals 229 and 231 of each switch are connected together by a wire 233, and a movable bridge member 234 operable by means of a push button 235, normally bridges the gap between the contacts 231 and 232. When the push button 235 is actuated, the member 234 will move out of electrical engagement with the terminals 50 231 and 232 and may bridge the gap between the terminals 227 and 229 of the switch, as will readily be understood by reference to Figure 11. The terminals 232 and 229 of adjacent switches are connected by wires 236 as shown. The push buttons 235 of the selector switch 188 are shown mounted in a suitable block 180 secured to the control panel 181. See Figures 1 and 8.

60 The fixed contacts 205 and 206 of each selector switch are connected by wires 237 and 238 to wires 239 and 241, respectively. These wires 239 and 241, as shown in Figure 1, are common to the fixed contacts 205 and 206 of the selector switch and, in like manner, the wire 214 is common to the fixed contacts of the relay coils 208.

65 The wire 239 is connected to one end of a relay coil 242, the opposite end of which has a wire 243 connecting it with a terminal 244 of an emergency stop switch 245, having a second terminal 246 spaced from the terminal 244, as shown. The gap between the terminals 244 and 246 is normally closed by the member 247, as shown. A wire 248 connects the terminal 246 of the emergency stop switch 245 with a fixed contact 249 of an up limit switch 251, having 75 a movable contact 252 adapted to be actuated

by an arm 253 carrying a roller 254 normally positioned in the path of the elevator frame, as will be noted by reference to Figure 1. The up limit switch 251, like the down limit switch 216, is normally closed and is actuated only in the event that the elevator accidentally over runs or passes beyond elevation 8. A wire 255 connects the movable contact 252 of the up limit switch 251 with the main line conductor 148. The relay 242 is connected to the wire 239 of the selector switch, as above described and is in the up circuit and a similar relay 257 has one end thereof connected with the wire 241 which is in the down circuit. The opposite end of the relay coil 257 is connected to a wire 243 by a wire 258. The relays 242 and 257 each have a fixed contact 259 connected by wires 261 to the wire 214, and each has a movable contact 262 adapted to be moved into electrical connection with the fixed contacts 259 when the relay coils 242 and 257 are energized. The movable contact 262 of the relay 242 has a wire 263 connecting it with the terminal 264 of a solenoid coil 265, the opposite terminal 266 of which is connected by a wire 267 to the terminal 268 of a solenoid 269. The terminal 271 of the solenoid 269 has a wire 272 connecting it with the movable contact 262 of the relay 257.

30 The motor 31, the operation of which is controlled by the selector switch 188 hereinbefore described, is of the direct current reversible type, and comprises a pair of conductors 273 and 274 connecting the armature winding thereof with a pair of movable contacts 275 and 276, respectively, of a motor control switch 271. This control switch further comprises a pair of fixed contacts 278 and 279 adapted to be engaged by the movable contacts 275 and 276, respectively, when the switch is closed. The movable contacts of the switch 271 are connected together by an actuator 281 operatively associated with the solenoid coil 265 so that when the latter is energized, the actuator will be operated to close the motor switch 271. The fixed contact 278 is connected to the main line conductor 148 by a wire 282 and the fixed contact 279 has a wire 283 connecting it with one side of a solenoid coil 163 of a magnetic brake of the type shown and described with reference to Figure 13. The other end of the solenoid 163 is connected by a wire 284 to the main line conductor 149, as shown. A gap 285 is provided in the wire 283 adapted to be bridged by a member 286 operable by means of a winding 287, having one end thereof electrically connected to a wire 288, having one end 50 connected to a wire 289 and its opposite end to a similar relay coil 291, the opposite end of which has a wire 292 connecting it to the wire 248.

60 A shunt circuit is connected across the motor circuit and comprises a wire 293, one end of which is connected to a terminal 294 and the opposite end thereof to a movable contact 295. The wire 296 connects the wire 293 with the motor conductor 273. The shunt circuit also comprises a wire 297 connected at one end to a movable contact 298 and having its opposite end connected to a terminal 299 spaced from the terminal 294 and adapted to be bridged by a member 301 which normally is in circuit-closing position and is adapted to be actuated by the relay 291. A suitable resistance 302 is interposed in the wire 297 for the purpose of imposing a resistance in the motor circuit. This resistance functions when the current supply to the motor has been cut off, and the motor continues to rotate after deener- 70 75

gization of the armature, whereby the motor tends to function as a generator, and thereby forces a current through the resistor 302. This acts to retard the action of the motor and thus aids in bringing the motor to a quick stop. The relay 287 has one end connected by a wire 303 to a wire 304 which, in turn, connects the wire 248 with the wire 267. The movable contacts 295 and 298 of the motor switch 305 are adapted to electrically engage a pair of fixed contacts 306 and 307, respectively. The movable contacts 298 and 295 are operatively connected together by an actuator 308 adapted to be actuated by the solenoid 269.

A movable contact 309 is also connected with the actuator 308 and is adapted to engage a fixed contact 311 having a wire 312 connecting it with a fixed contact 313 adapted to be electrically engaged with a movable contact 314, operatively connected with the actuator 281 and electrically connected to the wire 289 which also is connected to the movable contact 309. The movable contacts 276 and 298 of the motor switches 277 and 305 are electrically connected together by a wire 315.

Operation

In the operation of this novel apparatus when used for handling composition boards or flat material or articles, as shown in the present instance, the wall boards are delivered from the press onto the feeding conveyer 56 which, as hereinbefore stated, is of the power driven type. The switch buttons 185 and 186 control the operation of the feeding conveyer 56. When a board is delivered onto the feeding conveyer, the operator depresses the switch button 185, thereby closing the circuit to the motor 62 with the result that the rollers 57 of the feeding conveyer will be operated to feed the board onto the conveyer belts 55 of the elevator, it being understood that the elevator is at rest at elevation No. 3, as shown in Figures 1 and 8.

Before the board is fed onto the conveyer belts 55, however, the operator depresses the switch button 182, thereby starting the motor 79, which operates the belts 55. When the board has been feed onto the belts 55 of the elevator, said belts will subsequently be interrupted by reason of the leading edge of the board engaging the roller 132 and thereby breaking the circuit to the solenoid 145, whereupon the motor switch 154 is opened. Assuming that the board is to be delivered onto the upper elevation or tier No. 8 of drier 3, the operator will depress the push button 235 of the selector switch 188, corresponding to elevation No 8, whereby the circuit to the motor 31 is closed, thereby causing the elevator to ascend to elevation No. 8 where it will automatically come to rest because of the contact lever 204 disengaging the fixed contact 205 of elevation No. 8, when the elevator reaches said elevation.

When the elevator comes to rest at elevation No. 8, the operator will manipulate the lever 122 of the control valve 113 so as to cause the pressure fluid to be delivered into the cylinder 104, whereby the cross-head 101 is moved from the position shown in Figures 4 and 9, to that shown in Figure 5, thereby lowering the upper runs of the conveyer belts 55 to the positions shown in Figure 5, so that the board will be supported directly upon the conveyer rollers 65, as indicated by the dotted lines in Figure 5. As soon as the board engages the peripheries of the rollers 65, it will be laterally discharged from the elevator into the upper tier No. 8 of drier 3, it being understood that the roll-

ers 65 are preferably driven continually by the motor 78.

The circuit controlling the operation of the motor 31 when raising the elevator, operates in the following manner: When the elevator is in its normal load receiving position, at elevation No. 3, the contact lever 204 of the selector switch 188 will be positioned midway between the two contactors 205 and 206, as shown in Figures 11 and 12, out of electrical engagement therewith. All of the contact levers 204 of the elevations Nos. 4 to 8, inclusive, will be in electrical connection with the fixed contacts 205, while the contact levers 204 of elevations Nos. 1 and 2, below the normal loading position of the elevator will be in electrical connection with the fixed contacts 206, as illustrated in the wiring diagram, Figure 11. It will also be noted that the movable contacts 211 of the relays 208 are out of electrical contact with their complementary fixed contacts 212. When the operator depresses the push button 235 of the selector switch 188, corresponding to elevation No. 8, the member 234 of that particular switch 228 will bridge the gap between the contacts 227 and 229, thereby connecting the relay 208 with the main line conductor 149 as follows: From the conductor 149 through the wire 221 and contacts 217 and 215 of the down limit switch 216, which normally are in closed position; through the wire 214 to a contact 316 interposed in the wire 214, and thence through the wire 317 to the contact 229 of the lower switch 228, as shown in the lower left-hand corner of Figure 11.

Because of the members 234 of the switches 228 normally being in electrical connection with the contacts 231 and 232 thereof, current will flow from the terminal 316 through the wire 317 and through all of the switches 228 which normally are connected in series as shown. Because of the switch member 234 of the upper switch 235 bridging the gap between the contacts 227 and 229, the current will flow through the wire 226 to the relay 208 of elevation No. 8, thence through the wire 207, movable contact 204 and fixed contact 205 of the selector switch 188, through the wire 239, relay 242, wire 243, and through the contacts of the emergency stop switch 245, which normally is in closed position; thence through the wire 248 and contacts 249 and 252 of the up limit switch 251, which contacts also are normally in closed position. From the movable contact 252 of the up limit switch 251, the current flows through the wire 255 and back to the main line conductor 148, thereby completing the circuit. The closing of the above described circuit will cause the relay 242 to become energized, whereupon the movable contact 262 thereof is moved into electrical connection with the fixed contact 259 thereof, which results in the completion of a circuit through the solenoid 265, which operates the actuator and causes the motor switch 277 to be closed.

The circuit through the solenoid 265 is as follows: From the main line conductor 149, through the wire 221 and contacts 217 and 215 of the down limit switch 216, wires 214 and 261, through the contacts 259 and 262 of the relay 242 which, as hereinbefore stated, are in closed position, through the wire 263 to the terminal 264 of the solenoid 265, thence from the terminal 266 of the solenoid, through the wires 267 and 304 and a portion of the wire 248 to the fixed contact 249 of the up limit switch 251, thence through the closed contacts of the up limit switch 251 and through the wire 255 back to the main line conductor 148, thereby completing the circuit through 75

the solenoid 265, resulting in the closing of the motor switch 271.

Simultaneously, as the motor switch 271 is closed, the movable contact 314, which is connected to the actuator 281, will engage the contact 313 whereby current will be supplied to the relays 287 and 291, as follows: From the main line conductor 149, the current will flow through the wire 221, down limit switch 216, wire 214 and 10 through a portion of the wire 312 to the fixed contact 313; thence through the movable contact 314, wires 289 and 288, through the coils 287 and 291, because of the latter being electrically connected in parallel with the wire 248, which, in 15 turn, is electrically connected with the conductor 148 of the other side of the main line by reason of the wire 255 and closed up limit switch 251. Energization of the relay 287 will cause the member 286 to close the gap in the wire 283, thereby completing the motor circuit, whereupon the motor 20 will immediately function. Simultaneously, as the motor circuit is completed, the solenoid 163 of the magnetic brake will be energized to release the brake and at the same time, the resistance 25 302 shunted across the terminals of the motor will be cut out of the circuit because of the member 301 of the relay 291 opening the circuit through the resistance 302. The motor will then continue to function until the elevator reaches the upper 30 tier or elevation No. 8, whereupon the movable contact 204 of the selector switch will move into neutral position, as shown in Figure 12, whereby the circuit through the relay 208 will be broken, causing deenergization of the solenoid 265, with 35 the result that the motor switch 271 is automatically opened.

Simultaneously, as the switch 271 is opened, the current supply to the relays 287 and 291 and solenoid 163 will be cut off, whereupon the magnetic 40 brake will be set and the resistance 302 will be imposed across the terminals of the motor, thereby bringing the motor to a quick stop. As the elevator travels from its normal load receiving position at elevation No. 3 to the upper elevation 45 No. 8, all of the movable contacts 204 of the selector switch will move into electrical engagement with the fixed contacts 206, with the exception of the contact 204 of the uppermost selector switch 228, which will remain in neutral position until 50 the elevator starts its downward movement whereupon each of the contacts 204 above the elevator will assume positions in electrical engagement with their complementary fixed contacts 205.

To return the elevator to a lower elevation as, for example, its normal load receiving position or elevation No. 3, shown in Figures 1 and 8, the operator depresses the push button of elevation No. 3, whereupon the relay 208 of that elevation 55 will become energized, because of the contact lever 204 of the selector switch being in engagement with the fixed contact 206, as indicated by the dotted lines in Figure 11, thereby closing the circuit through the relay 257 whereby the circuit 60 is closed through the solenoid 269 of the motor switch 305. This circuit is as follows: From the main line conductor 149, through the wire 221, contacts 212 and 215 of the down limit switch 216, through a portion of the wire 214, wire 261, 65 through the closed contacts of the relay 257, thence through the wire 212 to the terminal 271 of the solenoid 269, from the terminal 268 of the solenoid, through a portion of the wire 267, wire 304 and a portion of the wire 248, through the 70 closed contacts of the up limit switch 251; and 75

thence through the wire 255 and back to the main line conductor 148. Such energization of the solenoid 269 will operate the actuator 308 to close the contacts of the motor switch 305 and, because of the contacts 309 and 311 being closed simultaneously as the contacts of the motor switch 305 is closed, the relays 287, 291, and brake coil 163 simultaneously become energized as described with reference to the motor switch 271, thereby causing the elevator to descend to elevation No. 3. The motor 31 controlling the operation of the elevator is of the reversible type, as hereinbefore stated, and the switch 271 causes the motor to rotate in a direction to raise the elevator, and closing of the switch 305 causes the motor to operate to lower the elevator.

The emergency stop switch 245 provides means whereby the operator may interrupt vertical movement of the elevator at any time should it become necessary. By opening this switch, the supply of current to the solenoids 269 and 265 is cut off, whereby the motor control switch 271 or 20 305 which may have been closed, will return to its normal circuit-opening position as shown in Figure 11. The circuits through the solenoids 265 25 and 269 are so related that but one can be energized at a time. The operation of the motor control switches 271 and 305 is controlled by manipulation of the push buttons 235 of the selector switch 188 mounted upon the raised control panel 30 181.

From the foregoing, it will readily be understood that by the use of the novel transfer unit herein disclosed in connection with a composition board press and one or more driers, into which the wet boards are to be transferred from the press, the operator will have complete control of the transferring of the boards from the press to the various tiers of the driers, by manipulation of the controls provided at the control station 123. While in the specification, the apparatus has been described as used for handling wet composition boards, it is to be understood that it may be used for various other materials of a flat nature as, for example, insulating material, asbestos, gypsum, sheets or blocks of cork insulation, metal sheets, and also articles conveyed in tote pans or trays which may be delivered into the tires or racks of such units as driers and annealing furnaces, and so forth. The limit switches 216 and 251 provide means for preventing overrunning of the elevator at its extreme lower and upper elevations, and the limit switch 123 provides means for automatically interrupting movement of the conveyer belts 55, when a board is delivered onto the elevator from the feeding conveyer 56. By means of the switch 178, the stop switch 128 may be rendered inoperative so that should the operator desire to deliver a board into one of the tiers of the drier 4, he will depress the switch 178 after the elevator has come to rest at the selected elevation and the motor 79 has been started by closing the switch 138, whereupon the conveyer belts 55 will be operated to deliver the board into the selected tier of drier 4, regardless of the limit switch 128. When the board has been delivered into the selected tier of the drier 4, the operator will interrupt further operation of the belts 55 by opening the switch 136. It will thus be seen that an operator positioned at the control station 123 may direct the boards or articles into selected tiers of the two driers, thereby greatly expediting the operation of thus transferring the boards from one place to another.

I claim as my invention:

1. In an apparatus of the class described, an elevator, operating means therefor, means for feeding articles to the elevator, spaced-apart conveyer belts on the elevator movable in the direction of movement of articles fed thereto and adapted to receive articles from said feeding means, means also on the elevator normally positioned beneath the upper portions of said belts and capable of laterally discharging articles therefrom, means for interrupting movement of the elevator at a predetermined elevation and fluid-operated means for causing an article to be transferred from said belts onto said discharging means to thereby laterally discharge the article from the elevator at said predetermined elevation. 10
2. In an apparatus of the class described, an elevator, operating means for the elevator, means for feeding articles thereto, conveyer means on the elevator adapted to convey articles in a direction lengthwise thereof, a second conveyer means on the elevator adapted to convey articles in a direction crosswise thereof, and fluid-operated means for imparting relative vertical movement 20 to one of said conveyer means to thereby transfer an article from one conveyer means to the other. 25
3. In an apparatus of the class described, an elevator, operating means therefor, means for feeding articles thereto, conveyer belts on the elevator movable in the direction of movement of articles fed thereto and adapted to receive articles from said feeding means, means for driving said belts, a plurality of rollers longitudinally disposed between said belts and adapted for constant rotation, said rollers normally being positioned below the upper portions of said belts, and fluid-operated means for relatively lowering said belts whereby an article supported thereon will be 30 transferred onto said rollers to be laterally discharged from the elevator. 40
4. In an apparatus of the class described, an elevator, operating means therefor, a plurality of elevations adapted to receive articles from said elevator, means for stopping the elevator at a selected elevation, means for feeding articles to the elevator, conveyer belts on the elevator disposed lengthwise thereof and adapted to receive articles from said feeding means, means for interrupting operation of said conveyer belts when an article is delivered onto the elevator, a plurality of longitudinally extending conveyer rollers arranged between said conveyer belts and normally out of engagement with an article supported thereon, and means whereby said conveyer belts may be actuated to cause an article supported thereon to be transferred directly onto said conveyer rollers, when the elevator comes to rest at a selected station, whereby the article may 50 be laterally discharged from the elevator at said selected elevation. 60
5. In an apparatus of the class described, an elevator, operating means therefor, a plurality of elevations adapted to receive articles from said elevator, means for stopping the elevator at a selected elevation, means for feeding articles to the elevator, a plurality of conveyer belts on the elevator disposed lengthwise thereof and adapted to receive articles from said feeding means, means for interrupting operation of said conveyer belts when an article is delivered onto the elevator, a plurality of longitudinally extending conveyer rollers arranged between said conveyer belts and 65 normally out of engagement with an article sup- 75
- ported thereon, means for constantly rotating said rollers, and means for lowering said conveyer belts when the elevator comes to rest at a selected elevation whereby an article supported thereon is transferred onto said conveyer rollers and laterally discharged from the elevator at said selected elevation. 5
6. An apparatus of the class described, comprising a frame, an elevator mounted therein, a plurality of conveyer means on the elevator arranged to discharge articles therefrom in different directions, a reversible motor for vertically moving the elevator, receiving means adjacent to said frame comprising a plurality of elevations each adapted to receive articles from said elevator, a control mechanism for said motor comprising two main switches and a plurality of selector switches, one for each elevation of said receiving means, said selector switches being electrically connected with said main switches 10 and adapted to cause either one or the other of said main switches to close, when one of said selector switches is actuated, whereby the motor will operate to move the elevator to the elevation corresponding to said actuated selector switch, 15 regardless of the vertical position of the elevator, and means for independently controlling said conveying means. 20
7. An apparatus of the class described, comprising a frame, an elevator mounted therein, a plurality of conveyer means on the elevator arranged to discharge articles therefrom in different directions, a motor for vertically moving the elevator, receiving means adjacent to said frame comprising a plurality of elevations, each adapted 25 to receive articles from the elevator, a control mechanism for said motor comprising a plurality of selector switches, one for each elevation of said receiving means, circuits electrically connecting said motor with said selector switches, means for causing said motor to operate and move the elevator to a selected elevation, when a certain selector switch is actuated, means for automatically interrupting operation of the motor when the elevator reaches said selected elevation, and 30 means for independently controlling said conveying means. 40
8. An apparatus of the class described, comprising a frame, an elevator mounted therein, a plurality of conveyer means on the elevator arranged to discharge articles therefrom in different directions, a reversible motor for vertically moving the elevator, a plurality of receiving means adjacent to said frame each comprising a plurality of vertically disposed tiers, each 35 adapted to receive articles from the elevator, a control mechanism for said motor comprising two main switches and a plurality of selector switches, one for each elevation of said receiving means, circuits electrically connecting the motor switches with said selector switches, means causing said motor to operate and move the elevator to a selected elevation, when a certain selector switch is actuated, means for automatically interrupting operation of the motor when the elevator reaches said selected elevation, and 45 manually operable means for independently controlling said conveying means, when the elevator is positioned at the selected elevation. 55
9. A transfer unit comprising a frame having an elevator mounted therein, receiving means adjacent to said unit each comprising a plurality of superposed tiers each adapted to receive articles from the elevator, a driving means for the elevator, a mechanism for controlling opera- 70 75

- tion of said driving means and whereby the elevator may be moved to a selected tier of one of said receiving means, conveyer means on the elevator adapted to discharge articles therefrom in a direction lengthwise thereof into a selected tier of one of said receiving means, other conveyer means on the elevator adapted to laterally discharge articles therefrom, and means for independently controlling the operations of said 5 conveyer means whereby when the elevator has been moved to a predetermined elevation, said conveyer means may be selectively operated to discharge an article from the elevator into a selected tier of one of said receiving means.
- 10 10. A transfer unit comprising a frame having an elevator mounted therein, a plurality of receiving means adjacent to said unit each comprising a plurality of superposed tiers adapted to receive articles from the elevator, a driving means for the elevator, a mechanism for controlling operation of said driving means and whereby the elevator may be moved to a selected tier of one of said receiving means, conveyer belts on the elevator disposed lengthwise thereof, an independent drive for said belts whereby they may be operated to discharge articles from the elevator into a selected tier of one of said receiving means, other conveyer means on the elevator, said conveyer belts normally being positioned to receive articles delivered onto the elevator, and fluid-operated means for actuating said conveyer belts to cause an article supported thereon to be transferred onto said other conveyer means whereby said article may be laterally discharged from the elevator.
- 15 11. A transfer unit comprising a frame having an elevator mounted therein, means for feeding articles to the elevator, a motor for raising and lowering said elevator, an electric circuit for the motor comprising two main switches adapted to control current flow therethrough, a receiving means positioned at one end of said elevator and a second receiving means positioned at one side thereof, each of said receiving means comprising a plurality of superposed tiers each adapted to receive articles from said elevator, a control mechanism for said motor comprising a plurality of selector switches, one for each tier of said receiving means, and each connected with said main switches, means electrically connected with said selector switches whereby when one of said selector switches is actuated, one of said main switches will be closed to cause the motor to operate to move the elevator to the selected tier of one of said receiving means, corresponding to said actuated selector switch, means for automatically opening said closed main switch when the elevator reaches the selected tier, whereby the elevator will come to rest, a plurality of conveyer belts on the elevator adapted to receive an article from said feeding means and capable of discharging an article from the elevator into a selected tier of the receiving means stationed at the end of the elevator, a plurality of conveyer rollers mounted between said belts and normally out of engagement with an article supported thereon, said conveyer rollers being adapted to laterally discharge an article from the elevator into a selected tier of the receiving means stationed at the side of the elevator, and independent means for controlling operation of said belts and said rollers, whereby an article may be discharged from the elevator into a selected tier of one of said receiving means.
- 20 12. A transfer unit comprising a supporting

frame having an elevator mounted therein, a motor for raising and lowering the elevator, a conveyer for feeding articles onto the elevator having an independent motor, a plurality of conveyer belts on the elevator normally positioned to receive articles from said feeding conveyer, said belts being adapted to discharge articles from the elevator at one end thereof, a plurality of conveyer rollers disposed lengthwise of the elevator between said belts and adapted to laterally discharge articles from the elevator, independent motors for said belts and conveyer rollers, fluid-operated means for vertically moving said belts with respect to said conveyer rollers to thereby transfer an article from the belts onto said rollers, and independent control means for all of said motors whereby they may be operated independently of one another to control the operation of said transfer unit.

13. A transfer unit comprising a supporting frame having an elevator mounted therein, a motor for raising and lowering the elevator, a conveyer for feeding articles onto the elevator having an independent motor, receiving means situated adjacent to said supporting frame and each comprising a plurality of superposed tiers, each adapted to receive articles from said elevator, a plurality of conveyer belts on the elevator normally positioned to receive articles from said feeding conveyer, said belts being adapted to discharge articles from the elevator at one end thereof, a plurality of conveyer rollers disposed lengthwise of the elevator between said belts and adapted to laterally discharge articles from the elevator, independent motors for said belts and conveyer rollers, means for vertically moving said belts with respect to said conveyer rollers whereby an article may be transferred from the belts onto said rollers, an operator's station comprising a plurality of selector switches adapted to control operation of the motor for raising and lowering the elevator, and whereby when one of said selector switches is actuated, said motor will operate to move the elevator to a selected tier of one of said receiving means, and other control means at said station for independently controlling the operation of said other motors.

14. A transfer unit adapted to receive flat sheets or boards from a press and selectively deliver said sheets to a plurality of superimposed tiers of a drying apparatus, said unit comprising an elevator, a plurality of power operated conveying means on the elevator selectively operable to discharge articles therefrom in different directions, a plurality of motors for operating the elevator and said conveying means, an operator's station, a control mechanism at said station for controlling the operations of said motors, said mechanism including a plurality of selector switches, one for each tier of said drying apparatus, and all of said motors and switches being electrically connected together whereby when the selector switch of a certain tier is actuated, the elevator will automatically move to said tier to deliver an article thereto, and independent control means for said power operated conveyer means.

15. In an apparatus for transferring flat composition sheets or boards from a press to a drier comprising a plurality of superimposed tiers adapted to receive said sheets, an elevator, operating means for vertically moving the elevator, a plurality of conveyer means on the elevator whereby articles may be discharged therefrom in different directions, means for feeding the

sheets onto the conveyer means of the elevator, drives for said conveyer means, an operator's station, and a plurality of control elements located at said station and associated with said operating means and said drives, whereby an operator stationed at said station may control the operation of the apparatus and selectively feed the sheets into selected tiers of the driers.

16. In an apparatus for transferring relatively large, wet composition sheets or boards from a press to a dryer including a plurality of superimposed tiers adapted to selectively receive said sheets, an elevator comprising a plurality of conveying means having independent drives, one of said conveying means being mounted for relative vertical movement upon the elevator, whereby the sheets may be transferred from one conveying means to the other, means for automatically interrupting traveling movement of the elevator when it reaches a selected tier, and pressure means for vertically operating said movable conveying means.

17. In an apparatus for transferring relatively large, wet composition sheets or boards from a press to a dryer including a plurality of superimposed tiers adapted to selectively receive said sheets, an elevator comprising a plurality of conveying means arranged to discharge articles from the elevator in different directions, pressure means for relatively vertically moving one of said conveying means upon the elevator, whereby the sheets may be transferred from one conveying means to the other, means for interrupting traveling movement of the elevator when it reaches a selected tier, and means for independently controlling said conveying means.

18. In an apparatus for transferring relatively large wet composition sheets or boards from a press to a dryer, including a plurality of superimposed tiers adapted to selectively receive said sheets, an elevator, a plurality of conveying means on the elevator, one of said conveying means being mounted for relative vertical movement upon the elevator, whereby the sheets may be transferred from one conveying means to the other, means for automatically interrupting traveling movement of the elevator when it reaches a selected tier, means for vertically operating said movable conveying means, and a control mechanism for the elevator and said conveying means, comprising a plurality of motors and interconnected selector switches, and an operator's station having a plurality of control elements associated therewith and whereby said motors and switches may be selectively and independently operated to thereby control the operation of the entire apparatus from a given point.

19. In an apparatus of the class described, an elevator, operating means for the elevator, means for feeding articles thereto, conveyer means on the elevator adapted to support and convey articles in a direction lengthwise thereof, a second conveyer means on the elevator adapted to support and convey articles in a direction crosswise thereof, and power-operated means for imparting relative vertical movement to one of said conveyer means to thereby transfer an article from one conveyer means to the other.

20. In an apparatus of the class described, an elevator, operating means therefor, means for feeding articles thereto, conveyer elements on the

elevator movable in the direction of movement of articles fed thereto and adapted to receive articles from said feeding means, means for driving said conveyer elements, a plurality of rollers longitudinally disposed between said elements and adapted for constant rotation, said rollers normally being positioned below the upper portions of the conveyer elements, and power-operated means for relatively lowering said conveyer elements whereby an article supported thereon will be transferred onto said rollers to be laterally discharged from the elevator.

21. In an apparatus of the class described, an elevator, operating means therefor, means for feeding articles to the elevator, spaced-apart conveyer elements on the elevator movable in the direction of movement of articles fed thereto and adapted to receive articles from said feeding means, means also on the elevator normally positioned beneath the upper portions of said conveyer elements and capable of laterally discharging articles therefrom, means for interrupting movement of the elevator at a predetermined elevation, and power-operated means for causing an article to be transferred from said conveyer elements onto said discharging means to thereby laterally discharge the article from the elevator at a predetermined elevation.

22. In an apparatus of the class described, an elevator, operating means therefor, a plurality of elevations adapted to receive articles from said elevator, means for stopping the elevator at a selected elevation, means for feeding articles to the elevator, conveyer elements on the elevator disposed lengthwise thereof and adapted to receive articles from said feeding means, means for rendering said conveyer elements ineffective to convey articles, when an article is delivered onto the elevator, a plurality of longitudinally extending conveyer rollers arranged between said conveyer elements and normally out of engagement with an article supported thereon, and means whereby said conveyer elements may be actuated to cause an article supported thereon to be transferred directly onto said conveyer rollers, when the elevator comes to rest at a selected station, whereby the article may be laterally discharged from the elevator at said selected elevation.

23. In an apparatus of the class described, an elevator, operating means therefor, a plurality of elevations adapted to receive articles from said elevator, means for stopping the elevator at a selected elevation, means for feeding articles to the elevator, a plurality of conveyer elements on the elevator disposed lengthwise thereof and adapted to receive articles from said feeding means, means for rendering said conveyer elements ineffective to convey articles, when an article is delivered onto the elevator, a plurality of longitudinally extending conveyer rollers arranged between said conveyer elements and normally out of engagement with an article supported thereon, means for constantly rotating said rollers, and means for lowering said conveyer elements, when the elevator comes to rest at a selected elevation, whereby an article supported thereon is transferred onto said conveyer rollers and laterally discharged from the elevator at said selected elevation.
